Inventor:

Jacot M. Mattix
By Chas. J. O'Neill Atty.

UNITED STATES PATENT OFFICE.

JACOB MANSON MATTIX, OF LOUISE, MISSISSIPPI.

TIMBER-ROLLER-SUPPORTING DEVICE FOR CARS.

1,384,770.

Specification of Letters Patent. Patented July 19, 1921.

Application filed June 3, 1920. Serial No. 386,158.

To all whom it may concern:

Be it known that I, JACOB MANSON MATTIX, a citizen of the United States, residing at Louise, county of Humphreys, State of Mississippi, have invented certain new and useful Improvements in Timber-Roller-Supporting Devices for Cars; and I do hereby declare the following to be a full, clear, and exact description of the invention, such as will enable others skilled in the art to which it appertains to make and use the same.

This invention relates to timber rollers commonly used to facilitate the loading and unloading of lumber and the like from railway cars, and more particularly to a device for supporting the timber roller on car door frames. These rollers are usually mounted on a beam adapted to be located adjacent the car door where the lumber is being loaded and unloaded.

The principal object of the invention is to provide a simple, cheap, and effective means of positioning or supporting the roller carrying beam so that the roller may be readily adjusted at will, to any desired height with respect to the car door or opening.

Another object is to so construct the supporting device that it may not only be adjusted vertically, but by virtue of its novel construction, the same may be manipulated to adapt itself for use in connection with door frames or jambs of varying thicknesses or sizes.

Another important feature lies in the fact that no tools are needed for making the various adjustments, yet at the same time, when once positioned the device will be firmly and positively locked in place, a simple manipulation of the device itself being all that is required to accomplish the desired securing and releasing thereof.

Briefly stated, the invention comprises a main supporting bracket of substantially L shape formation, having an enlarged head and a turned up lower portion in which one end of the roller carrying beam is supported. It is to be understood, that a pair of these devices are to be used, one for each end of the roller beam, as clearly shown in the drawing. The enlarged head portion of the device is provided with suitable holes, in any one of which is secured one end of a hook member, the hooked portion of said member adapted to embrace the rear face of the car door, frame or jamb. The enlarged head

portion of the support is rounded or cambered, so that when coöperating with the securing hook, after said hook has been adjusted in its proper hole, a cam action is employed in causing the hook to bite into the door jamb, upon the downward throw of the support, as will be more clearly set forth upon a further description of the device.

In the accompanying drawing:

Figure 1 illustrates a pair of the devices as applied to a car door frame supporting a timber roller;

Fig. 2 is a view, partly in plan and partly in section, on line 2—2 of Fig. 1;

Fig. 3 is a view, partly in elevation and partly in section, on line 3—3 of Fig. 1, showing the device as applied to a door frame and supporting the roller beam; and

Fig. 4 is an enlarged view more clearly showing the relation of the hook to the beam supporting bracket.

Referring to the drawings in detail, the invention comprises a bracket 1 which is adapted to support a beam 2 carrying the timber roller 3. Bracket 1, which is of substantially L shape, is provided with a turned up lower end portion 4 forming a support for the end of the beam 2. The bracket 1 is also provided with an enlarged head or upper portion 5, said head being slightly rounded or cambered.

Disposed in a preferably horizontal relation in the enlarged head 5 are a series of holes 6 adapted to receive one end of a coöperating member 7. This member 7 is provided with an angular bent portion 8 which is adapted to be inserted in any one of the holes 6 as desired, and the other end of the member 7 is constructed in the form of a pointed hook 9 which is for the purpose of biting into the car door jamb 10 when the device is in its adjusted position.

By providing bracket 1 with the holes 6 it will be apparent that by merely shifting the angular end 8 of the member 7 from one hole to another the device may be used on car door jambs of varying thicknesses. It will also be noted that the bracket 1, when rotated about any one of the holes 6, with the end 8 of the member 7 as a pivot, the hook 9 being in engagement with the door jamb 10, and the enlarged head 5 of said bracket 1 coöperating with the door frame, a cam action will be effected upon the downward throw of the lower end of the bracket 1, causing the biting of the hook 9 into the

door jamb 10 and the consequent locking or securing of the device as a whole in the desired position.

To release the support it is only necessary to force the lower end of the bracket 1 outwardly and upwardly, whereupon said bracket can be disengaged from the hook member 7 which will also release the said hook from the door jamb 10.

10 It is to be understood that applicant does not have to rely entirely upon the cam action for clamping his device in the various adjusted positions. Obviously the bracket can be placed against the door frame and the member 7 having its hook portion in engagement with the rear face of the door jamb and its angular end 8 inserted in the proper hole in the enlarged portion of the bracket, according to the thickness or width of the door jamb, a simple downward pressure exerted on said bracket will cause a binding action which will be sufficient to lock the device under ordinary conditions in the desired adjusted position. The support may be released by merely forcing the bracket upwardly, whereby the member 7 may be disengaged from the bracket.

This whole operation can be quickly and easily accomplished without the use of any tools whatsoever, and by the simple means of adjustment the same can be universally used in connection with cars of various types and sizes.

What I claim is:

35 1. An adjustable support for a timber roller beam, adapted to be secured to the upright member of a car door frame or the like, comprising a bracket, means for supporting said beam on said bracket, a hooked member coöperating with said bracket, one end of which is adapted to engage the bracket and the other end the upright member of the car door frame, for securing said bracket in its adjustable position.

40 2. An adjustable support for a timber roller beam, adapted to be secured to the upright member of a car door frame or the like, comprising a bracket, means on the lower end of said bracket for supporting said

beam, a series of holes arranged in the upper portion of the bracket, a hooked member coöperating with said bracket, one end of which pivotally engaging one of the holes in said upper portion of the bracket and the other end engaging the upright member of the door frame, for securing said bracket in its adjustable position.

3. An adjustable support for a timber roller beam, adapted to be secured to the upright member of a car door frame or the like, comprising a bracket, means on the lower end of said bracket for supporting said beam, an enlarged head formed on the upper portion of said bracket, a series of holes arranged in said enlarged portion, a hooked member coöperating with said bracket, one end of said member pivotally engaging one of said holes and the other end engaging the upright member of a car door frame, so that upon a partial rotation of the bracket about the selected hole as a pivot, from the horizontal to the vertical position, the upright member will be clamped between the hooked member and the bracket.

4. An adjustable support for a timber roller beam, adapted to be secured to the upright member of a car door frame or the like, comprising a pair of brackets, means on the lower end of each bracket for supporting the opposite ends of said beam, an enlarged head formed on the upper portion of each bracket, a series of holes arranged in said enlarged portions, a hooked member coöperating with each bracket, one end of said member pivotally engaging one of the holes of its respective bracket and the other end of each of said hooked members adapted to engage an upright member of a car door frame, so that upon the partial rotation of the bracket about the selected hole as a pivot, from the horizontal to the vertical position, and the subsequent downward pressure on the bracket in supporting the beam under working conditions, each upright member will be clamped between its associated hooked member and bracket.

In testimony whereof I affix my signature.

JACOB MANSON MATTIX.
